UNITED STATES PATENT OFFICE.

CARL A. LOHMAN, OF SEATTLE, WASHINGTON.

DRY-KILN.

1,274,911.

Specification of Letters Patent. Patented Aug. 6, 1918.

Application filed July 18, 1917. Serial No. 181,225.

To all whom it may concern:

Be it known that I, CARL A. LOHMAN, a citizen of the United States, and resident of the city of Seattle, county of King, and 5 State of Washington, have invented certain new and useful Improvements in Dry-Kilns of which the following is a specification.

My invention relates to dry kilns which are intended for the drying of lumber, and 10 comprises certain novel features of construction which will be hereinafter described and then particularly defined by the claims. The accompanying drawings show the particular construction which embodies the 15 features of my invention.

Figure 1 is a transverse sectional elevation of the kiln, and Fig. 2 a longitudinal sectional elevation of the same.

The kiln, as herein shown, really consists 20 of an interior kiln construction which is composed of some non-combustible structural material, such for instance, as brick, tile, concrete, or the like, and an outer inclosing casing which, for economy sake, 25 may be made of wood.

The kiln herein illustrated is one which is 30 of the single charge type, that is, the entire charge for the kiln is put in at one time and is left in place within the kiln until the drying operation has been completed, after 35 which it is removed and a new charge is put in place.

The inner or masonry structure comprises 40 upper section 1, which incloses the drying chamber, or that into which the lumber is placed. The lower section contains a heating chamber 2 and suitable flues for the control of the air supply and circulation. These 45 two sections are separated by a floor 10 upon which the rails for the support of the dry kiln trucks are placed. The heating chamber 2 has cross bars or supports 20, upon which are placed the heating pipes 3. This heating chamber is connected with the drying chamber, at one side of the kiln, by an 50 opening 11 which is left in the floor. This opening lies close against the side wall and the air from the heating chamber is discharged into the space 12 which exists between the side of the load and the side wall of the kiln.

At the opposite side of the kiln, a wall or partition 13 extends downward from the floor, at a point somewhat inward from the 55 side wall and to a level where it is beneath

the steam heating pipes 3. The flue 14 thus formed, communicates with the drying chamber by means of a hole left in the floor and with the heating chamber by means of a hole or port 15, which is left in the wall 13. 60

The opening 15 is controlled by means of a damper or valve 4, whereby the flow of air through this opening may be stopped when this is desired. I also provide fresh air supplying flues 5, which communicate with the heating chamber by means of openings, as 50. These openings may, or may not, be provided with dampers, but in any event, the flow of air through these flues is controlled in any manner found most suitable. 70

At the top of the drying chamber small flues 6 are provided, these extending to the outside air and being provided with a cap 60, or other suitable means, whereby the flow of air through them may be controlled. 75 At one side of the kiln a discharge flue or flues 7 is provided, this having communication with the interior of the drying chamber by means of opening, as 70, in the wall between them. This flue is also controlled 80 so as to use it or not, as may be desired.

I provide steam pipes 8, which are perforated, so as to discharge steam directly into the kiln. These pipes are preferably located upon the floor 10, although they may 85 be located in any position found desirable. The steam supply for these pipes is controlled separately from the supply for the pipes 3.

In drying lumber it is desirable that the 90 first step in the process should include the direct injection of steam into the drying chamber so as to contact directly with the lumber. This steaming of the lumber acts upon the pores of the lumber to put it in 95 better condition for the later extraction of the sap and moisture contained therein. After the lumber has been suitably steamed, the steam supply is cut off. During this preliminary stage in the drying operations, 100 the small discharge flue 6 may be opened so as to discharge surplus steam.

After this preliminary stage, the air contained in the kiln, is given a circulation, through the action of the heating pipes 3 and the flue system employed. Air, after being heated by the pipes 3, passes upwardly through the opening 11 into the space 12 at one side of the pile. The lumber being dried is supposed to be piled in horizontal layers 110

upon trucks, the different layers being separated by the use of the usual stickers. The heated air is thus forced through these layers from one side of the kiln to the other and is collected at the space 12 at this side of the kiln and passes downward through the flue 14 and is discharged through the opening 15 into the lower part of the heating chamber 2.

10 After the lumber has been exposed to this condition a sufficient length of time, I prefer that the kiln be supplied with fresh air taken directly from the outside, which is circulated through the lumber, and is then discharged without the kiln. This may be done by permitting free ingress of air through the flues 5 and by permitting the free discharge of the air from the vertical flue 7.

At this stage of the operation the damper 4 should be thrown upward into position where it would close the openings 15, thereby cutting off the closed circulation within the kiln. In this manner cool air may be admitted so as to cool down the lumber as it is in the kiln and to carry away the last remnants of moisture contained in the lumber.

The outer casing of the kiln has side walls which are composed of posts 25, which are 30 preferably each composed of a plurality of studs placed in contact. Upon these is secured an outer layer 26 which may be of any suitable type of lumber or other material. In the upper part of this frame work a stud 35 27 may be employed which is inclined inwardly toward its upper end so as to conform to the inclination which I prefer to give to the side walls of the kiln. This inward inclination to the walls of the kiln reduces the width of the spaces 12 at the side of the load, thereby cutting down the area of the passage about the load and tending to force the circulation to pass through the openings between the successive layers of 45 lumber in the pile.

The roof of the kiln contains joists 28 and a covering, as 29, which may be of any suit-

able material. The roof structure is preferably placed slightly above the masonry roof of the inner kiln structure, to thereby permit free expansion and contraction of the latter under heat. The outer insulating casing of the kiln is thus supported independently of the inner masonry structure.

What I claim as my invention is:

1. A dry kiln having a drying chamber, an air heating chamber beneath the floor of the drying chamber, the air heating chamber having its upper part connected at one side of the kiln with the drying chamber, the other side of the kiln having a flue connecting the lower part of the air heating chamber with the drying chamber, and a damper controlling this latter flue. 55

2. A dry kiln having a drying chamber, an air heating chamber beneath the drying chamber, and flues to produce a circulation between said chambers, steam discharging pipes, steam heating pipes located in the heating chamber, a damper controlling the circulation from the drying to the heating chamber, a discharging flue for the drying chamber and an air supplying flue for the heating chamber. 65

3. A dry kiln having a drying chamber, a heating chamber beneath the floor of the drying chamber, said floor having an opening at one side of the kiln forming a communication between said chambers, a flue at the other side of the kiln extending from the floor of the drying chamber downward alongside the heating chamber, and having openings communicating with the heating chamber, a damper controlling said openings, heating pipes arranged in a horizontal layer above the level of said opening into the flue, a discharge flue communicating with the drying chamber, and an air supplying flue extending lengthwise of the kiln and having openings discharging into the heating chamber. 75 80 85 90

Signed at Seattle, Washington, this 12th day of July, 1917.

CARL A. LOHMAN.
